REFRIGERATION

Carl Georg Munters, Stockholm, Sweden, assignor to Aktiebolaget Termisk Isolation, Stockholm, Sweden, a corporation of Sweden

Application March 31, 1934, Serial No. 718,392
In Sweden November 16, 1933

15 Claims. (Cl. 62—89)

My invention relates to refrigeration and more particularly to the conservation of cold produced by a refrigerating apparatus or the like.

One of the objects of my invention is to provide a refrigerator having a light, sturdy insulation.

Another object of my invention is to utilize the cooling effect of the primary cold producer to prevent condensation in insulation. In this connection, I produce a circulation of air in the insulation in a manner as hereinafter set forth.

The nature and advantages of my invention will be understood from the following description taken in conjunction with the accompanying drawings forming part of this specification, and 15 of which:

Fig. 1 is a vertical cross-sectional view of a refrigerator embodying the invention, and is taken on the line 1—1, of Fig. 3;

Fig. 2 is a view of part of the structure shown 20 in Fig. 1 on larger scale;

Fig. 3 is a vertical cross-sectional view taken on the line 3—3 of Fig. 1;

Fig. 4 is a horizontal sectional view taken on the line 4—4 of Fig. 3;

Fig. 5 is a horizontal sectional view taken on the line 5—5 of Fig. 1;

Fig. 6 is a plan view of a sheet of cardboard before bending, forming part of structure shown in other figures;

Fig. 7 shows another piece of cardboard;

Fig. 8 shows a modified form of the construction shown in Fig. 5; and

Fig. 9 shows a detail.

The refrigerator includes a cabinet which includes an inner shell or lining 10 open at the front and having flanges 11 which are secured to a frame member 12 as by screws 13. Frame member 12 may be made of wood. The lining 10 is made of sheet steel and may be porcelainized. It 35 is also provided with an opening 14 in its back vertical wall through which part of the refrigerating apparatus is inserted. The lining forms the border of the food space 15 of the refrigerator.

An outer insulation shell 16 is also secured to the frame member 12. The outer shell may be made up of a plurality of plates welded or otherwise secured together. Angle irons 17 may be provided at the corners to which the plates are secured. A refrigerator apparatus compartment is formed back of sheet 16 by suitable plating.

Between the inner and outer shells 10 and 16 are spaced cardboard boxes. In the embodiment shown, three such boxes are provided. The number may be more or less depending on the tem-

perature differential to be maintained between the food space 15 and the surrounding atmosphere or space. The three boxes or containers are designated 18, 19 and 20. These boxes are similar and the description of one will suffice.

Box 18 is essentially a five-sided cardboard box open at the front of the cabinet having sheets 21 of aluminum foil pasted or otherwise disposed on each side. Other material having bright surface for heat reflection may be used but the most 10 readily obtainable at the present time is sheets of aluminum of, for example, 0.007 millimeter in thickness.

The box is formed from sheet cardboard and can be advantageously made up from pieces as 15 shown in Figs. 6 and 7. A sheet of cardboard, which may be, for example, of the kind having smooth outer sheets and an intermediate corrugated sheet, and having a thickness of, for example $\frac{1}{8}$ to $\frac{1}{4}$ inch, is notched as shown in Fig. 6 20 and bent along the lines 22, 23 and 24 to form three sides of the box. An opening 25 is cut in the middle section to be in line with opening 14 of the liner and flanges 26 for this opening are formed by cutting on the lines 27 and folding on 25 the dotted lines 28. Side flanges 30 are formed by bending along the dotted lines 29. Side pieces or panels 32 of cardboard are then pasted to the flanges 30, thus forming the five sided box. Flanges 31 are provided at the open side of the 30 box thus formed. These are bent over on the dotted lines 33.

On mounting the cardboard box in the cabinet, these flanges 31 are secured to the frame member 12 as by nails 34. Preferably strips 35 of cardboard are glued onto the frame member 12 and the flanges 31 glued or cemented onto the cardboard strips 35 as well as secured by nails. It is also preferable to glue or cement pieces of paper or cloth over the meeting edges of pieces 32 and 40 flanges 30. The boxes are to be tight at these edges and also tight where secured to the frame member 12. When mounted, the flanges 26 are glued or cemented to a cardboard collar 37 aligning the openings at the back of the cabinet for the 45 refrigerating unit. The collar 37 is made tight with the liner as by being flanged at 38 and glued or cemented to the liner. Collar 37 is secured to the outer shell as by being flanged at 40 and pressed between the outer shell and a wooden 50 frame 41 by screws 42. Cement, glue or other tightening means may also be here applied.

The sheets of metal foil are pasted on each side of the cardboard boxes. No foil is, however, pasted on flanges 31 or 26.

The cardboard boxes with their bright metal surfaces are nested within each other to provide air spaces 46, 47, 48 and 49. These air spaces are tight against leakage of air except for certain holes hereinafter specified. The boxes may be spaced a distance of, for example, 2 to 2.5 centimeters (about $\frac{3}{4}$ to 1 inch).

Sheets of aluminum foil 50 and 51 are also pasted or glued onto the outer surface of the liner 10 and the inner surface of the outer shell 16 respectively.

The refrigerating apparatus includes an evaporator 52 mounted on a pipe or heat exchanger 53 passing through an insulated wall part 54 which fits into the openings at the rear formed in the inner and outer sheets and the cardboard boxes. The member 53 is connected to that part of the refrigerating apparatus 153 which is outside the insulated food space. The type of refrigerating apparatus is immaterial. It may be of the compression type or the absorption type with any desired form of heat input, as for example a burner 154. Other sources of cold may also be used such as ice or solidified carbon dioxide. With certain types of cold producers, the opening in the rear is not necessary. The type of apparatus may be that shown in Pats. No. 1,609,-334, 1,910,853 and 2,037,782.

Where a removable wall section such as 54 is used, it may be made as a slab of cork having an inside plate 55 and an outside plate 56. To provide tightness, a gasket 57 is mounted on an outturned flange 58 on the liner against which plate 55 bears and a gasket 59 is provided between plate 56 and the outer shell.

The door is constructed in similar manner. It includes an outer shell 60 secured to a wooden frame member 61. A wooden frame member 62 is secured to member 61. A sheet of metal foil 63 is glued or cemented to the inside surface of shell 60. A sheet of cardboard 64 with sheets of metal foil on each side thereof is placed against frame member 61 which spaces it from member 60 by, for example, three fourths of an inch. A box 65 is made with sides 66 which are nailed or glued, or both, to member 62. This member is coated with metal foil except for the side flanges 66. One or more additional such boxes 67 may be inserted. An inner door shell 68, coated 50 with metal foil on the side toward box 67 sets into a rubber gasket 69 and is held in place as by screws fastened into member 62. Parts 62, 65 and 67 may be, for example, a separate sub-assembly.

Suitable tightening means such as a metal strip 88 fastened to the door and bearing against a fiber strip 89 fastened to member 12 may be employed between the door and the outer shell 16. The spaces between the parallel cardboard pieces in 60 the door may be on the order of 1 inch. Less spacing, as shown, may be used but obviously the wider the spacing, the less the material for a given door width. This spacing is hereinafter more fully discussed.

For the purpose of preventing condensation within the insulation, I provide means for circulation of air. A pipe 70 is provided extending through the closure or panel 54 affording direct communication between the outer atmosphere 70 and the food space. In the embodiment shown, this pipe is of 5 millimeters inside diameter. In the lining 10 is a hole or port 71 somewhat above the bottom of the food space. This hole, in the embodiment shown is of 8 millimeters diameter. In the center top of box 18 is a 10 millimeter

hole 72. In the bottom center of box 19 is a 10 millimeter hole 73. In the bottom of box 20 to one side of the hole in box 19 is a 10 millimeter hole 75. The outer shell is similarly apertured as at 76.

By means of these apertures, a very slow circulation of air is produced from the outside atmosphere through pipe 70 into the space 15, thence through hole 71 into space 46, thence through hole 72 into space 47, thence through hole 73 into space 48, and through holes 75 and 76 back to the outer atmosphere. The air passing into the space 15 is cooled to the lowest temperature. The cooling should be such that on subsequent flow through the spaces of the insulation, condensation does not occur. A natural circulation is set up in the aforesaid direction of flow due to the fact that the column of colder air between the elevation of pipe 70 and the elevation of outlet aperture 76 is heavier than the corresponding outside column of warm air.

Refrigerator cabinets have been previously insulated with spaced sheets of aluminum foil. It has been previously believed that the best spacing is about one centimeter. I have discovered that so close a spacing is unnecessary where the temperature difference to be maintained is as small as in refrigerator cabinets. I have found that the spacing can be increased more than twice the recommended spacing without having serious convection currents in the intervening air spaces. The spacing can be, for example, 2 to 2.5 centimeters, or $\frac{3}{4}$ to 1 inch. At these spacings, convection currents will take place between the vertical walls but I have determined that with the insulation herein described, advantages are obtained which more than offset losses due to the small convection movement of the air. It is particularly difficult to build up a suitable structure for holding unbacked metal foils in an irregular wall structure as in a refrigerator. The frames conduct heat and are expensive if made so as to prevent losses in the frames. By using self-supporting boxes, I avoid corner frames and I avoid transverse conduction at the corners, and I entirely avoid intermediate spacing members which would conduct heat. Furthermore I provide equal temperature spaces around the food space separated from each other except at the front frame. This makes it possible to provide a slow, uniform air circulation throughout the insulation. With separate overlapping packages, heat conducting paths are formed and, to have a proper circulation, connections between the packages would be necessary, which is complicated.

Condensation in insulation of a refrigerator is a difficult problem. Condensation takes place when air is cooled so that moisture precipitates therefrom. It is therefore desirable that air does not flow from the atmosphere through the insulation to or toward the food space. To prevent this, I make use of a preponderance of weight between columns of air to force circulation of air outwardly through the insulation so that condensation cannot take place within the insulation. I conduct air into the food space so that it is first cooled and moisture may therefore deposit out in the food space. Thus I ensure dry air passing through the insulation and prevent moisture which would corrode the metal surfaces and otherwise harm the insulation and detract from the insulation properties. Since I use very few layers, it is important that they shall not have a film of water on them.

The door spaces may likewise be provided with means for flow of air outwardly from the food space although a door can readily be made tight with respect to the outer atmosphere and forced air circulation is not of such importance as in the cabinet itself. As an example, a hole may be provided in plate 68 at the level of hole 71, a hole may be provided in member 67 at a high part thereof, a hole in member 65 at a low part thereof, a hole in member 64 at a high part thereof, and a hole in the bottom of member 60. In some instances, natural leakage may be relied on instead of holes but I prefer definite holes with the spaces otherwise air-tight so that a positive controlled circulation may be obtained. The holes should be of sufficient size to provide adequate circulation to prevent condensation but so small as to prevent appreciable loss of cooling effect due to the flow. The aperture into the food space may advantageously be higher than the aperture between the food space and space 46 so that a cold down-leg is assured and the supply of the air to the food space can advantageously be through the rear window adjacent the evaporator so that good cooling of the air is obtained.

However, the openings may be arranged in a variety of ways so long as the outward movement is assured. The holes should be arranged to give a preponderance of specific gravity of air column so that the flow is directed from the inside to the outside. It is preferred to so arrange the holes that there is movement of air all around the refrigerated space. By means of the nested box construction I am able to provide a path of flow of air which entirely encompasses the refrigerated space.

The air need not circulate entirely through the insulation but may circulate from the food space, downwardly in the first outer space, upwardly through a second outer space of higher temperature and back to the food space for drying by cooling.

The hole 71 is preferably positioned so that water will not enter the same on washing out the interior of the refrigerator. It may be placed, as shown, on a shelf supporting projection in the liner.

Another door construction is shown in Fig. 8 in which cardboard boxes 80 and 81 are nailed and/or glued, together with member 64, onto the frame member 61. This door construction includes a Bakelite frame 82 and rubber gasketing 83. Long screws may pass through plate 68 and into member 61. It will be seen that I provide a light door construction which is easy to build.

It will be seen that the amount of material necessary to handle for making the insulation is small. Sheets of cardboard and aluminum foil can be stored in small space and readily formed in the process of manufacture.

Fig. 9 shows a moisture separator which may be inserted in the aperture 71. It includes a casing 99 having baffles 91 therein and an end piece 92 having a central opening. Baffles 91 are apertured to provide a tortuous path for gas and cut at their lower parts to allow separated moisture to flow into the food space 15.

Instead of having the opening 75 in the bottom of box 20, this opening may be higher up or at the top so that complete circulation takes place through all the air spaces.

The pipe 70 may be arranged to extend downwardly for some distance within the food space and having a lower liquid sealed opening in a drip

pan and a branch connected to space 46 whereby the air is cooled and dehydrated due to the cooling source and lead directly into space 46.

It will be noted that an important factor is that air shall not pass inwardly through the insulation to or toward the food space. The outside shell of the insulation can be made tight, but even in such case it is advantageous to have a cold air column acting against the outside shell to allow breathing of the insulation due to barometric variations or otherwise without condensation and to guard against unintentional leaks.

It will be understood that the invention is not limited to the embodiment disclosed and that many variations are possible within the scope and spirit of the invention.

What I claim is:

1. A refrigerator having a framework, an inner liner attached to said framework, an outer shell attached to said framework, and intermediate 20 nested spaced self-sustaining cardboard boxes attached to said framework and having openings therein for movement of air, said openings being at different elevations, said liner having an opening in the lower part thereof below at least one of 25 the box openings and affording communication between the interior of the liner and a space adjacent one of said boxes, said boxes being surfaced with aluminum foil.

2. A refrigerator having an outer shell, an inner liner spaced therefrom, said outer shell and said liner being open on a common vertical side to provide a door opening, a plurality of nested, light, non-metallic self-sustaining box-like members 35 between said shell and said liner, closure means between the liner and shell and members at said vertical side, said members being appreciably spaced from each other and from the liner and from the outer shell, said members being surfaced with bright metallic layers and surrounding all 40 walls of the liner whereby intermediate spaces having both horizontal and vertical portions are formed between the liner and the outer shell, said liner having an opening in its lower part forming an air flow passage between the interior space of 45 the liner and a first intermediate space and said members having additional openings at different elevations whereby air circulation is produced due to difference of specific weight of different vertical 50 air columns and air circulation is induced in the horizontal portions of the intermediate spaces due to the vertical columns of different specific weight.

3. A refrigerator having an outer shell, an inner liner spaced therefrom, said outer shell and said liner being open on a common vertical side to provide a door opening, a plurality of nested, light, self-sustaining rigid cardboard box-like members between said shell and said liner, closure means between the liner and shell and members at said vertical side, said members being spaced from each other and from the liner and from the outer shell on the order of one half an inch to an inch, said members being surfaced with bright metallic layers and surrounding all walls of the liner 65 whereby intermediate spaces having both horizontal and vertical portions are formed between the liner and the outer shell, said liner having an opening in its lower part forming an air flow passage between the interior space of the liner and a 70 first intermediate space and said members having additional openings at different elevations whereby air circulation is produced due to difference of specific weight of different vertical air columns and air circulation is induced in the horizontal 75

75

- portions of the intermediate spaces due to the vertical columns of different specific weight.
4. A refrigerator having an outer shell, an inner liner spaced therefrom, said outer shell and said liner being open on a common vertical side to provide a door opening, a plurality of nested light, non-metallic self-sustaining box-like members between said shell and said liner, closure means between the liner and shell and members at said vertical side, said members being appreciably spaced from each other and from the liner and from the outer shell, said members being surfaced with bright metallic layers, said liner having an opening forming a communication between the interior space of the liner and a first intermediate space and said members having additional aperturing whereby air circulation is produced due to difference of specific weight of different vertical air columns.
5. A refrigerator having an outer shell, an inner liner spaced therefrom, said outer shell and said liner being open on a common vertical side to provide a door opening, a framework at the edges of and connecting the outer shell and the liner, a plurality of nested, light, self-sustaining cardboard box-like members between said shell and said liner attached at their edges to said framework, said members being appreciably spaced from each other and from the liner and from the outer shell, said members being surfaced with bright metallic layers and surrounding all walls of the liner whereby intermediate spaces having both horizontal and vertical portions are formed between the liner and the outer shell, said liner having an opening in its lower part forming an air flow passage between the interior space of the liner and a first intermediate space and at least some of said members having openings at different elevations whereby air circulation is produced due to difference of specific weight of different vertical air columns and air circulation induced in the horizontal portions of the intermediate spaces due to the vertical columns of different specific weight.
6. Refrigerator cabinet construction comprising an outer shell, a plurality of self-sustaining box-like structures nested one within the other, said plurality of boxlike structures being formed of poor heat conducting material and mounted in the outer shell in spaced relation to the walls thereof, a liner inwardly of the innermost structure constructed to form a food storage compartment, certain of said structures having a surface of a nature to obstruct flow of heat through the structure towards the center of the cabinet, and means for restricted air communication between the storage compartment and spaces adjacent said boxlike structures.
7. A device of the character described comprising a structure having walls forming a compartment, means for insulating to retard heat flow through said walls comprising a preformed insulating unit spaced from but having walls corresponding to the walls of said compartment-forming structure, said insulating unit being constructed of poor heat conducting material of relatively light weight but of sufficient body to be self-sustaining and being surfaced with metallic reflective material to hinder loss by radiation, and means for restricted air communication between said compartment and space adjacent said insulating unit.
8. A device of the class described comprising inner and outer shells, insulating means between said shells comprising a plurality of preformed spaced self-sustaining boxlike structures of aluminum surfaced cardboard nested one within the other and means for restricted air circulation in spaces between the said boxlike structures.
9. Cabinet construction comprising a door frame, a self-sustaining heat flow obstructing insulating unit mounted on said door frame comprising a boxlike structure formed of non-metallic poor heat conducting material and having a metallic heat reflecting surface.
10. Insulation comprising a plurality of preformed generally box shaped heat flow obstructing units nested in spaced relation and having walls of self-sustaining non-metallic poor heat conducting material provided with metallic heat reflecting surfaces.
11. Insulation for use with walls forming an enclosure to retard heat flow through the walls of said enclosure comprising a self-sustaining heat flow obstructing insulating unit in the form of a boxlike structure composed of non-metallic poor heat conducting material and having a metallic reflecting surface.
12. A device of the character described comprising walls forming a compartment, means for insulating to retard heat flow through said walls comprising a series of nested preformed insulating units about said compartment disposed in separated relation to provide intermediate air spaces, and means for producing circulation of air outwardly from the compartment between said nested units whereby moisture condensed within said nested units will be carried outwardly to the atmosphere.
13. Refrigerator construction comprising walls forming a storage compartment, spaced nested insulating units about said compartment providing air spaces, cooling means within said compartment, means for permitting breathing between said compartment and said air spaces, whereby incoming air will be cooled due to the cooling means in said compartment and thereby reduced in moisture content and such dried air may take up moisture as it flows in the air spaces provided by said nested insulating units.
14. Refrigerator construction comprising walls forming a storage compartment, spaced nested insulating units about said compartment providing air spaces, cooling means within said compartment, means for permitting breathing between said compartment and said spaces, whereby incoming air will be cooled due to the cooling means in said compartment and thereby reduced in moisture content and such dried air may take up moisture as it flows in the air spaces provided by said nested insulating units, the construction being such that air flow is over a substantial portion of the insulation.
15. Refrigerating construction comprising walls forming a storage compartment, spaced nested insulating units about said compartment, cooling means within said compartment, means for admitting air directly into the compartment in the vicinity of the cooling means, and means for discharging air from the compartment through said nested units in a circuitous path to take up moisture from said insulating units.
